UNITED STATES PATENT OFFICE

ROBERT HELMERT, OF BERLIN-LICHTERFELDE, AND BENNO JOHANNESSEN, OF BERLIN-TEMPELHOF, GERMANY, ASSIGNEES TO C. LORENZ AKTIENGESELLSCHAFT, OF BERLIN-TEMPELHOF, GERMANY

SELECTOR

Application filed August 29, 1928, Serial No. 302,715, and in Germany September 6, 1927.

The invention relates to switches or selectors suitable, for example, for automatic telephone and remote control systems, of the type that are provided with several sets of brushes, which are movable in one direction only and capable of being operated with a continuous sliding motion as well as a step-by-step motion. The selection of one of the available sets of brushes is, in the present case, effected 10 electrically by an auxiliary or brush selector.

According to the invention, the contact bank of the brush selector, in order to avoid leading flexible conductors to each brush set, is rigidly connected to the brush sets of the 15 bank contact groups, and the brush selector is set by the same driving mechanism as that which operates the brush sets of the bank contact groups.

Constructional examples of the invention 20 are diagrammatically represented in the accompanying drawings in which:—

Fig. 1 represents a connector in which the brush selector is directly operated by the driving mechanism.

25 Fig. 1^a shows a detail of construction.

Fig. 2 shows the circuit diagram therefor.

Fig. 3 shows additional arrangements for the group selectors.

Fig. 4 shows additional arrangements for 30 the line finders.

In Fig. 5 the principle of a brush selecting operation, by to and fro movements of the switch rod carrying the brush sets, is represented.

35 Referring to Figure 1, the brush sets 2, 3, 4, 5 and 6 wipe over the contact bank 7 and are mounted, together with the contact bank 12 of the brush selector, on the switch rod 1. The brush sets 2—6 are electrically connected

40 with corresponding contacts of the contact bank 12 by means of the cable 48, whilst the brushes 13 of the brush selector are connected by the flexible cable 16 to the distributor 17. By means of the switch rod 1, the auxiliary

45 selector brushes 30 are guided over the control contact bank 31, secured on the frame, in order to effect switching operations in accordance with the position of the brush sets 2—6.

50 The driving mechanism consists of a con-

tinuously rotating shaft 8 and an electromagnet friction coupling. When the magnet winding 9 is energized, the armature 10 is driven by the wheel 11, secured to the rotating shaft 8. The brushes 13 are connected to the armature 10 by the locking rod 14, which is guided in its sliding motion by the bearings 15, 18 and 19 on the switch rod 1, so that the driving mechanism acts directly on the brushes 13 of the brush selector whilst the brush sets 2—6 are driven through the ratchet pawl 20, which couples the switch rod 1 with the locking rod 14. The locking pawl 21 is provided in order to prevent the setting member from falling back.

55 The operations will first be described for a connector and with reference to Figs. 1 and 2. The numerical current impulses which serve to control the connector are caused by the earthing of the line *a* in the well-known manner.

60 On sending a current impulse, the winding 22 of a control device is energized through earth, *a*-line, winding 22, battery to earth (see Fig. 2). The armature 23 is attracted and the contact set 24 changed over. The locking tooth 25 moves into a hole in the locking rod 14 whereby the locking pawl 20 is pushed out. The electromagnetic friction coupling is en- 65 ergized through the circuit shown in Fig. 2, (earth, contact 24, contact 26, winding 9, bat- tery, earth) so that the locking rod 14, together with the brushes 13, is raised, whilst switch rod 1, with the contact bank 12, re- 70 mains stationary. After the brushes 13 have moved a step on the contact bank 12, the locking pawls 20 and 21 fall into the next hole of the locking rod 14, whilst locking tooth 25 of the control device returns to its upper stop 27, 75 so that the brushes 13 are locked in this position.

80 During this operation, the projection 28 of the locking tooth 25, on its rotation about the bolt 29, has caused the contact 26 to open in order to break the circuit of the driv- 85 ing means. When the numerical impulse has ended, the armature 23 falls off so that the locking lever 25 returns into its normal posi- 90 tion under the action of the spring 32. On the sending of the next numerical current im- 95 100

pulse, the above described operations are repeated.

The slow-acting relay U is inserted at every current impulse by the contact 24 and falls off, in a well-known manner, only when the series of current impulses has been completed (see Fig. 2). The coupling means is now energized through earth, contact u, position 0 of the control contacts 31, brush 30, positions 1—10 of the contact bank 12, brush 13, contact 26, magnet winding 9, battery, to earth. The locking rod 14 and the switch rod 1 are then coupled together by the locking pawl 20. When the brush 30 leaves the position 0 of the control contacts 31, the circuit for the coupling means is opened so that the setting member, held from falling by the locking pawl 21, remains stationary. On the second series of current impulses being sent, the same operations are repeated as with the first series, with the difference that the locking pawl 20 is out of the range of operation of the locking tooth 25, so that locking rod 14 and switch 1 are moved together.

In the group selector (Fig. 3), the brush selection is effected by numerical current impulses as in the case of the connector, and no change is made in the operation of the brush selector but the movement of the brush sets over the bank contact groups takes place with uniform motion. After the slow-acting relay U has fallen off, the coupling is inserted as in the case of the connector. The control device 31 is, however, in this case not interrupted between the positions 0 and 1 so that the setting member is raised above position 1 until a testing operation on a free bank contact group takes place.

In order that the control device may also be used for locking the setting member during the testing operation, the lower stop 38 of the locking tooth 25 is constructed so as to be movable in accordance with Fig. 3 and, in this particular example of construction, it is formed by a leaf spring. In the normal position of the switch rod 1, the stop 38 presses the spring 38 down, so that the latter is located in a position corresponding to the stop 40 in Fig. 1. When the switch rod 1 is raised, after the completion of the numerical selection, the spring 38 swings out and presses the locking tooth 25 against the stop 27. During the testing operation, the winding 9 is energized. The armature 23 is attracted so that the setting member is momentarily stopped by the locking tooth 25 whilst the circuit of the coupling is opened by the contact 26. (Figs. 1 and 2).

In the case of selectors with free selection over the contact bank 12 and the contact bank 7 (for example, line finders according to Fig. 4), the locking pawl 20, which in the normal position of the switch rod 1 is moved out by a sloping member 40, falls into the locking rod 14. On step 1, the circuit for the wind-

ing 22 (for example, by means of the control contacts 31) is opened so that the armature 23 falls off and the circuit for operating the coupling is again closed through the contact 26. The driving mechanism now moves the locking rod 14 and the switch rod 1 together. The locking tooth 25 rests, under the action of the spring 41, on the stop 27. During the testing operation on a bank contact, the winding 22 is energized, whereby the setting member is held as in the case of the group selector.

A second constructional example for the setting of the brush selector is given in Fig. 5. The armature 10 of the electromagnetic friction coupling rests, in this case, on the switch rod 1. The setting of the brushes of the brush selector is effected by to and fro movements of the switch rod 1. The brushes 13 of the brush selector are, in this case also, mounted on the locking rod 14 which is guided on the switch rod 1.

The numerical current impulses are received by the winding 22 of the control device. When the winding 22 is energized, the armature 23 is attracted and thus inserts the electromagnetic coupling through the contact 24, whilst the locking tooth 25 which, in this case does not engage in the locking rod 14, is moved into the uppermost hole of the locking rod 47 mounted on the switch rod 1. The driving mechanism now raises the switch rod 1 which moves the locking rod 14, by means of the pawl 44, until the winding 9, as described in the first constructional example, is disconnected by the opening of the contact 26. The locking rod 14 remains locked in the position reached by the locking tooth 21, whilst the switch rod 1 falls back, since the locking pawl 41, on the first step, finds no locking tooth on the rod 47. The locking tooth 25 remains locked since its hook 46 has engaged under the spring 45, thus keeping the contact 26 open. Only on the completion of the numerical impulse, when the armature 23 again falls off, is the hook 46 released by the spring 45 so that the contact 26 is again closed by the return of the locking tooth 25.

When the first series of current impulses is finished, according to the first constructional example, the switch rod 1 is lifted, without cooperation of the control device, by two steps so that the locking pawl 41 no longer lets the switch rod 1 fall back. The second series of current impulses then effects the step-by-step lifting of the switch rod 1 together with the locking rod 14.

We claim:—

1. In a selector for automatic telephone and remote control systems, the combination with sets of field brushes and their contact banks, of a main brush selector carrying said field brushes, and an auxiliary selector the contact bank of which is rigidly connected to and

movable with the field brushes and main brush selector.

2. In a selector for automatic telephone and remote control systems, the combination with sets of field brushes and their contact banks, of a main brush selector carrying the field brushes, an auxiliary brush selector whose contact bank is rigidly connected to the main brush selector, and a common driving means 10 for driving both selectors.

3. In a selector for automatic telephone and remote control systems, the combination with field brushes and their contact banks, of relatively movable main and auxiliary brush 15 selectors, the latter having its contact bank rigidly connected to and movable with the former, and a driving means for driving both selectors.

4. In a selector for automatic telephone and 20 remote control systems, the combination with field brushes, their contact banks, and a main brush selector, of an auxiliary brush selector whose contact bank is rigidly connected to the main selector, and operating means for actuating the main brush selector for a selecting action through the auxiliary brush selector.

5. In a selector for automatic telephone and 30 remote control systems, the combination with sets of field brushes and their contact banks, of a main brush selector carrying said field brushes, an auxiliary brush selector whose contact bank is rigidly connected to the said main brush selector, and a driving mechanism which directly drives the brushes of the auxiliary brush selector and is coupled to the main brush selector after the brush selecting operation is completed.

6. In a selector for automatic telephone and 40 remote control systems, the combination of a brush setting member, a brush selector whose contact bank is rigidly connected to the said member, a lifting rod carrying the brushes of the brush selector, a driving mechanism which directly drives the lifting rod, and 45 means for coupling the lifting rod to the brush setting member after the brush selecting operation is completed and for the purpose of selecting the individual contact.

7. In a selector for automatic telephone and 50 remote control systems, the combination of a brush setting member, a brush selector whose contact bank is rigidly connected to the said member, a driving mechanism which effects a to and fro movement of the setting member, and means whereby the brushes of the brush 55 selector are carried along with the setting member in one direction of movement but are held in the opposite direction of movement so that the said brushes are advanced with 60 reference to their contact bank.

8. In a selector for automatic telephone and 65 remote control systems, the combination of a brush setting member, a brush selector whose contact bank is rigidly connected to the said member, a driving mechanism which effects

a to and fro movement of the setting member, an electromagnetic locking device which allows the brushes of the brush selector to move with reference to the setting member, and a second locking device which takes over the locking when the brush setting member moves out of its normal position. 70

9. In a selector for automatic telephone and remote control systems, the combination of a brush setting member, a brush selector whose 75 contact bank is rigidly connected to the said member, a lifting rod guided by said brush setting member and carrying the brushes of the brush selector, a constantly rotating driving shaft, electromagnetic means for coupling the said driving shaft to the said lifting rod, a magnetic control device whose armature controls the operation of said electromagnetic coupling means, means for coupling the lifting rod to the brush setting member after the 80 brush selecting operation is completed, and detents for preventing the falling of the lifting rod and the setting member. 85

In testimony whereof we have affixed our signatures.
